METHOD OF AND APPARATUS FOR PURIFYING HYDROCARBON OIL.

Application filed August 22, 1925. Serial No. 51,746.

Our invention relates to a method of and apparatus for treating hydrocarbon oils and is particularly, though not exclusively, adapted for treatment of cracked gasoline.

5 Hydrocarbon oils are usually treated to decolorize, deodorize, or otherwise purify the same before sale. It is common practice to pass the hydrocarbon oil through some treating medium such as fuller's earth, bentonite, or similar material, for the purpose of decolorizing, deodorizing, or otherwise treating the same. Heretofore it has been usual in effecting such treatment of hydrocarbon oils to place the proper quantity of 10 treating medium, which has been previously especially prepared, in a suitable shell or tower and then pass the hydrocarbon oil therethrough to receive treatment, this process being continued until the treating 15 medium becomes spent or the efficiency becomes reduced to such an extent that it is no longer practicable to pass the hydrocarbon oils therethrough. It then becomes necessary to stop the flow of oil, permit the 20 tower or other receptacle to cool off and then remove the spent treating medium. Thereafter, the tower is again charged with treating medium and the same process again started, these alternate chargings and dis- 25 chargings taking place whenever the treating medium becomes spent. This method, which may be termed batch operation, is expensive in time, labor and materials, and the hydrocarbon oil is not in all cases treated 30 with the desirable degree of uniformity. The oil receiving the first treatment from the fresh treating medium will be more effectively treated than the oil passing through the treating medium which is al- 35 most spent.

It is the general object of the invention to provide a generally improved and cheapened member of and apparatus for treating hydrocarbon oils so as to deodorize, de- 45 colorize, purify, or otherwise treat the oil.

It is another object of our invention to provide a method of and apparatus for treating hydrocarbon oils in which the treatment will be substantially continuous as dis- 50 tinguished from treatment in batches.

It is a further object to provide a method of and apparatus for preparing treating medium so as to form a porous or open column through which oil vapors may be passed for treatment. Other minor objects will be apparent as the specification proceeds.

The method in a preferred form may be briefly described in connection with a preferred form of apparatus for carrying out the process. A suitable treating tower or 60 treating chamber is provided, and into this tower, the treating medium is fed, preferably in form of strings or other comparatively finely divided masses. In order to facilitate the introduction of the treating medium into the treating tower in the desired form, it is preferred to mix the treating medium, for example, fuller's earth, bentonite, or the like, with water so as to 65 form a paste or mud which may then be forced or extruded from nozzles by means of a suitable pump, mud press, or the like. The threads or strings are dropped down in the tower and vaporized hydrocarbon oil passes into the tower, preferably near the 70 lower end and upwardly therein to the top, at which point it passes out to a suitable condenser or the like. The hot oil vapors serve to at least partially dry the mud strings so as to form relatively hard masses 75 which in falling one on the other will build up a column having substantial interstices to permit the proper passage of the hydrocarbon oil vapors. In addition to or in lieu of drying the mud strings by means of the 80 hydrocarbon oil vapors, we may also employ steam for heating the mud during passage through the nozzles or at some other location. The method contemplates a substantially continuous passage of hydrocarbon oil vapors through the column of 85 treating medium and the addition of string-like, or other form of treating medium, to the top of the column and removal of quantities of spent treating medium from the 90 bottom of the column. The spent treating medium, after being broken up when necessary, is removed from the bottom of the tower and conducted to a suitable container 95 where it may be treated to remove entrained oil and possibly to partially revivify the same.

In the drawings which show, for illustrative purposes only, a preferred form of apparatus for carrying out the process—

Fig. 1 is a partially diagrammatic view 100 of apparatus for carrying out the process and embodying features of inventions;

Fig. 2 is an enlarged sectional view of a detail.

In said drawings, 5 indicates a shell or 110 what may be termed a treating tower. This tower preferably will be lagged or insulated

on the outside as by means of suitable insulating material 6 applied to the surface thereof. Within the tower is preferably a bottom or partition which may be in the 5 form of a shaking grate 7 which may be actuated by suitable means, such as the crank 8 on the outside of the tower. At the upper end of the tower we provide means for introducing treating medium and in the 10 form shown, we employ a plurality of nozzles 9—9 connected to a manifold 10, which manifold is in turn connected to a suitable device, such as a mud pump, press, or the like, 11, for a purpose to be later described. 15 These nozzles, or some part of the nozzle system, are preferably steam-jacketed and, in the form shown, each nozzle 9 is provided with an annular chamber or jacket 12 which may be connected to a steam pipe 13 for 20 the purpose of heating the material passing through the nozzles. The treating medium, which may be fuller's earth, bentonite, or the like, depending upon the particular requirements, is preferably introduced into 25 the treating chamber in the form of a paste or mud. We may prepare the paste by mixing the finely powdered or granulated material with water so as to form a putty-like mass thin enough, however, to be readily extruded through the nozzles 9—9 and into the 30 treating tower 5. It will be observed that by forming the treating medium into a paste or mud, waste dusts from pulverizing mills may be used effectively. The mud is 35 fed to the pump or press 11 in the usual way and the press forces the mud through the manifold 10 and out through the nozzles 9—9, the mud issuing therefrom in the form of string-like masses which drop down into 40 the treating chamber and onto the grate 7, if such grate be provided. The strings will be longer or shorter depending upon the consistency of the mud, the speed of extrusion, the speed of drying, etc. It will sometimes 45 be desirable to heat the mud before it enters the treating tower and in such cases, steam is introduced into the jackets 12 so as to heat the mud to such an extent that it will be at least partially dried as soon as it 50 emerges into the treating tower 5.

The hydrocarbon oil is vaporized in a suitable still 14 and a pipe 15 conducts the vapors into the tower 5 near the lower end thereof. Obviously, the vapors may be 55 passed through a fractionating tower before entering the treating tower. The vapors pass out of this treating tower near the upper end, through a pipe 16 leading to a suitable condenser 17 for condensing the 60 treated vapors. Now, with all except the very low boiling point hydrocarbon oils, the hot vapors entering the tower through the pipe 15 on coming in contact with the string-like masses from the nozzles 9—9, 65 will dry the mud strings so that they become

comparatively hard or firm so that the lower strings falling upon the grate 7 will support subsequent strings falling on top and form a very porous or open-work column of 70 treating medium inside the tower as diagrammatically illustrated in the drawings. The height of the column in the tower may be ascertained as by means of a suitable "crow's foot" 18 extending through a stuffing box in the top of the tower. Obviously, by moving the crow's foot until it contacts with the top of the treating column, 75 one is apprised of the approximate height thereof.

Now, the vapors passing through the 80 treating column are given the treatment afforded by the specific treating medium employed, and the treated vapors then emerge from the tower and are condensed or otherwise treated. 85

After a time, the material at the lower part of the treating column becomes spent and by our process is removed while the upper part of the column is being built up by fresh treating medium entering through 90 the nozzles 9—9. The lower part of the column may become quite hard and lumpy and if this happens, the shaking grate 7 may be actuated by the crank 8 to break up the lumps and permit the small particles 95 to fall through the grate and into the lower cone-shaped bottom 19 in the treating tower.

Some oil vapors are likely to condense in the tower and drop into the spent treating medium in the cone-shaped bottom of 100 the tower. This condensate may be refluxed back into the still 14 through the connection 20, if desired.

At suitable intervals, a large valve 21 in the bottom of the tower 5 may be opened 105 and the spent treating medium below the grate together with the entrained oil which has not been returned to the still, drops down into a container or receptacle 22. After the lower portion of the tower 5 has 110 been cleared, the valve 21 is again closed. During the time that treating medium is being removed from the bottom of the column and added to the top of the column, the flow of vapors may continue uninterrupted. 115 Since the column is continuously being built up at the top and removed at the bottom, the vapors receive substantially the same treatment at all times, thus distinguishing sharply from a batch 120 operating process in which the vapors passing through the fresh treating medium receive more efficient treatment than those passing through later when the entire batch is more or less spent.

The spent treating medium in the receptacle 22 may then be treated to remove the entrained oil, and for this purpose, we may introduce a suitable solvent, such as gasoline or other light oil, through the pipe 23, 130

for dissolving out a part of the oil which is then removed through pipe 24 and used for whatever purpose it may be fitted. Instead of dissolving out the oil with a solvent, we may introduce water, steam, or super heated system through the pipes 25, 26, 27 for vaporizing the oil, which vapors may pass out of the receptacle 22 and into a suitable condenser 28 where the vapors are condensed. When steam is employed and the entrained oil vaporized, the treating medium is partially revivified and may be used over again, for example, in percolating type treating towers. The spent treating medium may pass from the receptacle 22 through the valve 29 and be conducted away by a suitable conveyor, or the like, 30.

It will be seen that by means of our improved process and apparatus, we are enabled to afford a substantially continuous treatment of hydrocarbon oils as distinguished from a batch treatment. It will be observed further that hydrocarbon oils treated by our process will receive substantially uniform treatment day in and day out so that a uniformly finer product results. Waste products, such as mill dusts, may be used as part or all of the treating medium since the latter is preferably introduced in the form of mud. Time, labor, and material are saved by our continuous process as distinguished from a batch operating process. The spent treating medium after removal from the treating tower may itself be treated to remove entrained oil and to partially revivify the same.

While the invention has been described in some detail, we do not wish to be limited to the specific method and apparatus herein described, since changes may be made within the scope of the invention, as defined in the appended claims.

We claim:

1. Method of treating hydrocarbon oil which includes forming a treating medium into a paste or mud forming the paste into strings and permitting the same to accumulate to form a porous column of treating medium, vaporizing the hydrocarbon oil and passing the vapors through said column to be treated thereby and out through the top thereof.

2. In a method of treating hydrocarbon oil which includes forming a treating medium into a paste or mud forming the paste into string-like masses and permitting the same to accumulate to form a porous column of treating material, vaporizing hydrocarbon oil and passing the vapors through said column of treating medium, said vapors serving to at least partially dry said string-like masses whereby the same are hardened and the column will remain porous so as to permit the passage of vapors therethrough,

said vapors receiving treatment from the treating medium of said column.

3. The method of treating hydrocarbon oil which includes forming the treating medium into a paste or mud forming the paste or mud into string-like masses, heating the string-like masses to at least partially dry the same, permitting the strings to accumulate to form a porous column of treating medium, vaporizing the oil and passing the vapors through said column and out through the freshly added masses.

4. The method of treating hydrocarbon oil which includes adding water to pulverized treating medium to form a mud or paste, forming the paste into a plurality of string-like masses and permitting the same to accumulate to form a porous column of treating medium, vaporizing the oil and passing the vapors through said column of treating medium and out through the freshly added portions of said string-like masses, breaking up the spent treating medium at one end of said column and removing the same while the column is being built up at the opposite end.

5. The method of treating hydrocarbon oils which includes vaporizing the oil, forming a treating medium into a paste, dividing the paste into relatively small masses and dropping the same through the vaporized oil to at least partially dry the same whereby said small masses may pile up and form a porous column of treating medium and passing the hydrocarbon vapors through said column for treatment.

6. In a device of the character described, a treating tower, a plurality of nozzles leading into said tower, means for forcing treating medium in the form of a paste or mud through said nozzles to form string-like masses, means for vaporizing hydrocarbon oil and conducting the vapors to said treating tower, said string-like masses forming a porous column of treating material in said tower through which said vapors may pass, and means for condensing said vapors after passage through said treating tower.

7. In a device of the character described, a treating tower for receiving a column of treating medium, a nozzle connecting with said tower, means for driving treating medium in the form of a mud or paste through said nozzle, means for heating the mud or paste during passage through said nozzle to at least partially dry the same, and means for conducting hydrocarbon oil vapor to said tower.

8. In a device of the character described, an insulated treating tower, a shaking grate therein, a plurality of nozzles connecting with interior of said tower, means for forcing treating medium in the form of a mud or paste through said nozzles and permitting the masses of paste issuing from said nozzles

to accumulate on and above said grate to form a porous column of treating medium, a still for vaporizing hydrocarbon oil, means for connecting said still and treating tower 5 for conducting oil vapors from said still to the lower end of said column of treating medium, means for condensing the oil vapors after passage through said column of treating medium, means for permitting the 10 removal of spent treating medium and entrained oil from said tower beneath said grate, and means for receiving said spent treating medium and entrained oil.

9. The method of treating hydrocarbon oils which includes, forming a treating medium into a paste or mud, dividing the paste into relatively small masses, drying the small masses and forming a porous column of treating medium by adding said small masses at the top thereof, and passing the oil vapor upward through said porous column, for treatment and to have a drying effect on the newly added masses. 15 20
